UNITED STATES PATENT OFFICE.

KONRAD SCHUTZ, OF BROOKLYN, NEW YORK.

STRENGTHENING DEVICE FOR SHOES.

Application filed October 18, 1927. Serial No. 226,864.

This invention relates to strengthening devices for shoes and more particularly to such devices as are used to prevent the crumpling and wrinkling of the counter portion of the shoe.

It has been found that the upper part of the heel portion of a shoe, especially shoes of the Oxford type, are wrinkled and crumpled by the constant taking off and putting on of the same, by the wearer.

The object of this invention is to provide a stiffening means for strengthening the upper part of the heel portion of the shoe, so that the wearer may put on the shoe or take it off without breaking down the back part of the shoe. This means also prevents the shoe from slipping off the wearer's foot.

This and other like objects are accomplished by the novel construction and combination and arrangement of parts, herein-after described and shown in the accompanying drawing, forming part of this disclosure, and in which:—

Figure 1 is a perspective view of a shoe showing my device as applied thereto.

Figure 2 is a cross sectional view showing my device as applied to a shoe.

Figure 3 is a plan view of the device.

Figure 4 is a cross sectional elevational view.

Figure 5 is a front view.

Figure 6 is an elevational view.

Referring to the drawings, a shoe 7 is shown with an upper heel portion 8, having the device applied thereto. The heel strengthening device is composed of two sections, 9 and 10 respectively, as shown in Figure 6, these sections being pivoted to each other at 11.

The section 10 is provided with a plurality of hooks 12, which are adapted to engage the portion 9 so that the structure will act as one piece.

The hooks 12 are provided with means for frictionally engaging the part 9, and also the part 10 is provided with means for limiting the downward movement of the part 9.

The part 10 has fixed to its inner side a pad 13 which may be made of rubber or a fibrous substance.

In operation, the part 9 is placed on the outside of the shoe, as shown in Figure 2

and then the part 10 rotated downwardly on the pivot 11, so that the hooks 12 engage the leather of the heel part of the shoe and the part 9.

It will be seen that this operation securely and firmly holds the strengthening device on the shoe.

It is obvious, from the description set forth, that the invention herein presented provides a convenient and desirable means for strengthening and keeping in good appearance the heel portion of Oxford shoes.

From the device herein described, the wearer is assured that the heel portion of his shoe will be rigid and unwrinkled, while he is taking the shoe off and while putting it on.

Having thus described my invention, what I claim as new and desire to secure by Letters Patent, is:—

1. A strengthening device for the heel portions of shoes, comprising two arcuate metal strips hinged to each other, one of said strips being adapted to embrace the outside of the shoe, and the other strip having a pad fixed to its inner side, and hooks to engage the leather of said shoe and the first mentioned strip.

2. A device for strengthening the heel portions of Oxford shoes, comprising two metal strips hinged to each other, one of said strips being adapted to engage the outer portion of the shoe and the other strip being adapted to engage the inner portion of the shoe, the last named strip having a pad mounted on its inner surface and provided with hooks to engage the leather of a shoe and the first mentioned strip.

3. A device for strengthening the heel portion of shoes, comprising a pair of arcuate metallic strips hinged together, one of said strips lying on one side of the leather of a shoe and the other strip lying upon the other side, the second mentioned strip being provided with a cushion to engage the wearer's foot and also having a series of hooks to pass over the edge of the heel portion of the shoe and engage the first mentioned arcuate strip.

In witness whereof I have affixed my signature.

KONRAD SCHUTZ.
